UNITED STATES PATENT OFFICE

THOMAS H. BYRON, OF ELIZABETHTON, AND RALPH H. CARTER, OF JOHNSON CITY, TENNESSEE, ASSIGNORS TO AMERICAN GLANZSTOFF CORPORATION, OF NEW YORK, N. Y., A CORPORATION OF DELAWARE

APPARATUS FOR FILAMENT TREATMENT

Application filed March 14, 1932. Serial No. 598,866.

The present invention concerns a new method whereby filaments upon perforated spools may be dried from one side only.

In the manufacture of artificial filaments, for example, by the viscose process, the spool process is sometimes used. According to this method the filaments are extruded into an ordinary acidifying setting bath, passed from there in the wet state directly upon perforated spools, and, while upon these spools wet-treated in the usual manner. This wet-treatment comprises the ordinary desulfurization, bleaching, washing, deacidifying, etc. It has been found that when artificial filaments are used and wet-treated upon these perforated spools, and then dried, an uneven shrinkage of the drying filaments takes place. This is caused by the fact that the inner layer of the filaments resting directly against a rigid spool bodily contacts thereagainst, forming a very tight tape. The outer layer of filaments similarly contract against the inner layer, and the result is unevenness of shrinkage. With filaments thus unevenly shrunk the physical characteristics of the same are altered in succeeding lengths. That is, the denier of the filament appears to change and the surface of the individual threads appears to possess varying degrees of hardness, according to the tension to which various lengths have been subjected. All of this results in the production of a finished production which has uneven dyeing qualities. In an effort to obviate the unevenness of the dyeing it has been suggested that the filaments be dried from one side only, re-wet and then re-dried from the same side. Between the first drying and the second drying, the filaments may be rewound and twisted if desired upon another spool so that those filaments which were originally on the inner side of the cake will later be upon the outer side. These steps have produced a filament which possesses a very even dyeing effect inasmuch as very even shrinkage results. In order that these filaments might be treated more expeditiously and advantageously in the plants, the present apparatus has been devised.

One object of the present invention is to provide a means whereby a plurality of spools of filaments may be simultaneously dried from one side only.

Another object of the present invention is to provide a means of the type set forth which is so constructed that the filaments are, at all times, held out of contact with the faces of a container which might tend to damage them.

Other objects will become apparent from a perusal of the following specification and a study of the accompanying drawing, in which:

Figure 1 discloses a cross sectional view of a series of spools in superimposed position within our new type container.

Figure 2 is a detail view in cross section of one of the sub-containers for holding the individual spool, and

Figure 3 is a top plan view of the container disclosed in Figure 2.

The filaments (1) are wound upon perforated spools (2) and these spools are placed within a holder (3). This holder (3) comprises an outer body portion (4) provided at its bottom with inturned edge portions (5). A pair of gaskets (6) and (7) are arranged above and below the inturned portions (5). The inturned portions and the gaskets (6) and (7) are arranged so that a circumferential space (8) is formed. From between these two gaskets a holder (9) for the filaments comprising a three-arm upstanding cylindrical framework, is provided. The spools slip about this inner container, as shown in Figure 2, and the filaments (1) are thus held away from contact of the side walls (4) of the container. The lower edge (2') of the spool contacts with the upper gasket (6) of the container, thus forming an air-tight connection. The upper end (2'') of the spool is adapted to be pressed against the lower gasket (7) of the next container in the superimposed series. The filaments are wound upon the perforated spool so that they cover all of the perforations of the same, and by sealing the upper and lower edges of the spools with the circumferential gaskets (6) and (7), it is seen that an air-tight seal is provided and

- the filaments upon the spools may thereupon be dried from one side only, inside. A shell (10) in the form of a cylinder with an open end (11) surrounded by a gasket (12) is provided in order that a series of spools may be treated at one time. The spools are placed within the open end container so that the open end of the individual spool containers faces the end (11) of the container (10).
- 10 When a sufficient number of spools in their containers have been placed within the cylinder (10), the cylinders are placed in a drying position as shown at (13) and hot air or other drying media is introduced to the opening (14). (13) are positioning lugs acting to locate the cylinder over the opening (14), which should be as wide as possible in order to freely admit the passage of the air. This air passing up through the center of the 20 spools has access only to the inner surface of the same and therefore dries the filaments upon the spools from the inside only, the outside filaments remaining in a wet state until the latter portion of the drying operation.
- 25 When the drying has been completed, the cylinder (10) still containing the spools may be lifted bodily and transported to the position of the next operation, where the spools may be removed from the container.
- 30 As will be seen from a study of the steps outlined above, our new process provides a means whereby a series of spools may be now treated in an advantageous manner in about the same length of time originally required if one spool were to be wrapped so that it would be dried from one side only.
- Having now set forth our invention as required by the patent statutes, what we desire to claim is:
- 40 1. In a device for simultaneously drying several units of spooled filaments from one side only, in combination an open-ended tube, a series of individual containers sized to fit within the tube, the said containers being 45 placed in superimposed condition within the said open-ended tube, the tube then being placed around positioning lugs on a plate.
2. In a device for simultaneously drying several units of spooled filaments from one side only, in combination an open-ended tube, a gasket arranged within and adjacent the open end, a series of individual containers sized to fit within the tube, the said containers being placed in superimposed condition 50 within the said open-ended tube, the tube then being placed around positioning lugs on a plate.
3. In a device for simultaneously drying several units of spooled filaments from one side only, in combination, an open-ended tube, a gasket arranged within and adjacent the open end, a series of individual containers sized to fit within the tube, a spool holding 60 means in each container, the said containers being placed in superimposed condition with- 65
- in the said open-ended tube the tube then being placed around positioning lugs on a plate.
4. In a device for simultaneously drying several units of spooled filaments from one side only, in combination, an open-ended tube, a gasket arranged within and adjacent the open end, a series of individual containers sized to fit within the tube, said containers comprising tubes open at both ends, one of 70 said ends being bent inwardly a short distance to form a shoulder, the said containers being placed in superimposed condition within the said open-ended tube, the tube then being placed around positioning lugs on a plate.
5. In a device for simultaneously drying several units of spooled filaments from one side only, in combination, an open-ended tube, a gasket arranged within and adjacent 80 the open end, a series of individual containers sized to fit within the tube, said containers comprising tubes open at both ends, one of said ends being bent inwardly a short distance to form a shoulder, gaskets on the face of the shoulder, the said containers being placed in superimposed condition within the said open-ended tube, the tube then being placed around positioning lugs on a plate.
6. In a device for simultaneously drying 90 several units of spooled filaments from one side only, in combination, an open-ended tube, a gasket arranged within and adjacent the open end, a series of individual containers 100 sized to fit within the tube, said containers comprising tubes open at both ends, a shoulder formed on one of said ends, gaskets on the inner and outer faces of the shoulder, whereby the edges of a spool within one of the said containers will be adapted to contact with the outermost of the said gaskets.
7. In a device for simultaneously drying several units of spooled filaments from one side only, in combination, an open-ended tube, a gasket arranged within and adjacent the open end, a series of individual containers 110 sized to fit within the tube, said containers comprising tubes open at both ends, one of said ends being bent inwardly a short distance to form a shoulder, gaskets on the inner and outer faces of the shoulder, the inner end of the spool held in each container being adapted to contact with the innermost of the said gaskets.
8. In a device for simultaneously drying 120 several units of spooled filaments from one side only, in combination, an open-ended tube, a gasket arranged within and adjacent the open end, a series of individual containers 130 sized to fit within the tube, said containers comprising tubes open at both ends, a shoulder formed on one of said ends, gaskets on the inner and outer faces of the shoulder, the inner end of the spool held in each container being adapted to contact with the innermost

of the said gaskets, the said containers being placed in superimposed condition within the said open-ended tube.

9. In a device for simultaneously drying several units of spooled filaments from one side only, in combination, an open-ended tube, a gasket arranged within and adjacent the open end, a series of individual containers sized to fit within the tube, said containers comprising tubes open at both ends, one of said ends being bent inwardly a short distance to form a shoulder, gaskets on the inner and outer faces of the shoulder, the inner end of the spool held in each container being adapted to contact with the innermost of the said gaskets, the tube then being placed around positioning lugs on a plate.

10. In a device for simultaneously drying several units of spooled filaments from one side only, in combination, an open-ended tube, a gasket arranged within and adjacent the open end, a series of individual containers sized to fit within the tube, said containers comprising tubes open at both ends, a shoulder formed on one of said ends, gaskets on the inner and outer faces of the shoulder, the inner end of the spool held in each container being adapted to contact with the innermost of the said gaskets, the tube then being placed around positioning lugs on a plate, said plate being perforated for the passage of the drying medium.

11. In a device for simultaneously drying several units of spooled filaments from one side only, in combination, an open-ended tube, a gasket arranged within and adjacent the open end, a series of individual containers sized to fit within the tube, a spool holding means in each container, the said containers being placed in superimposed condition within the said open-ended tube, the tube then being placed around positioning lugs on a plate, said plate being perforated for the passage of the drying medium.

12. In a device for simultaneously drying several units of spooled filaments from one side only, in combination, an open-ended tube, a gasket arranged within and adjacent the open end, a series of individual containers sized to fit within the tube, a spool holding means in each container, the tube then being placed around positioning lugs on a plate, said plate being perforated for the passage of the drying medium.

13. In testimony whereof we affix our signatures.

THOMAS H. BYRON.
RALPH H. CARTER.
